UNITED STATES PATENT OFFICE.

HENRY CSANYI, OF NEW YORK, N. Y.

SIGNAL APPARATUS.

1,251,184.

Specification of Letters Patent. Patented Dec. 25, 1917.

Application filed January 15, 1915. Serial No. 2,377.

To all whom it may concern:

Be it known that I, HENRY CSANYI, a citizen of the United States, residing at New York, in the county of New York and State of New York, have invented new and useful Improvements in Signal Apparatus, of which the following is a specification.

This invention relates to signals, and particularly to such signals as are carried by vehicles. The invention is particularly applicable to rear end signals intended to prevent collisions, and a principal object of the invention is to produce a very simple and efficient rear end signal which will operate to indicate whether the vehicle carrying the signal is moving or stopped. Many accidents to automobiles occur due to the fact that a car ahead will turn suddenly to the right or left without warning to a car following.

The invention is applicable to such automobiles, or other road vehicles, and one of the objects of the invention when applied to that use, is to enable the signal to indicate the direction the vehicle will take in making a turn.

Further objects of the invention will appear more clearly hereinafter.

The invention consists in the general combination of parts and features hereinafter described, all of which contribute to produce an efficient signal.

The preferred embodiment of my invention will be particularly described in the following specification, while the broad scope of my invention will be pointed out in the appended claims. In the drawings—

Figure 1 is a side elevation illustrating my signal as applied to the rear end of a railway car or train.

Fig. 2 is a rear elevation of a modified form of the invention indicating the application of my signal to the rear end of an automobile, in which relation the signal may perform the functions of the ordinary automobile tail light.

Fig. 3 is a side elevation of a semaphore such as is shown in Fig. 2 and representing the same detached from the operative mechanism of the signal.

Fig. 4 is a vertical section taken through a part of the casing of the signal and illustrating the mechanism and the manner in which it controls the character of the message or signal which is transmitted to a person in the rear of the vehicle carrying the signal.

Fig. 5 is a plan and partial section through the parts shown in Fig. 4.

Before proceeding to a detailed description of the invention it should be stated that the particular construction of the signal device set forth herein is merely by way of illustration, as obviously the invention may be embodied in many different constructions. The invention, however, should embody means for indicating a signal or message to a person in the rear of the vehicle, the character of which is controlled in some way from the driving gear of the vehicle so that when the vehicle stops a danger signal appears and when the vehicle starts the danger signal is eliminated. In other words, when the vehicle stops, it automatically displays a danger signal. This arrangement tends to prevent accidents from rear end collisions. As applied to the rear of an automobile my signal will not only indicate whether the automobile is stopped or moving, but it will also indicate, by reason of its driving connection with the vehicle, whether the automobile is to proceed to the left or right.

Referring more particularly to the parts, and especially to Figs. 4 and 5, 10 represents a signal device such as a semaphore arm, which is preferably mounted on a rock shaft 11 so that it can occupy a position understood to indicate danger, that is, that the vehicle carrying the signal has stopped, said semaphore being arranged to move automatically to another position such as that indicated by the dotted lines 10^a, at which time the accepted meaning of the message would be "safe," that is, that the vehicle is in motion.

I prefer to control the rock shaft from a moving part of the running gear of the vehicle so that when the vehicle is in motion a movement is transmitted to the rock shaft.

which will move the signal from its "danger" position and which will raise the semaphore to its "safe" position. This is preferably accomplished through the medium of 5 a centrifugal device 12, which is preferably mounted in a suitable weather-tight case 13.

This centrifugal mechanism may be of any desired construction. I have represented it as consisting simply of a hollow shaft 14, 10 one end of which projects from the case so as to be attached to a flexible shaft 15. The flexible shaft 15 is driven at a relatively high speed of rotation from some moving part of the vehicle. The inner end of the shaft 15 14 is mounted in a suitable bearing 16. On the hollow shaft 14 a suitable collar 17 is provided, to which centrifugal arms 18 are pivotally attached at 19, said arms provided with adjustable weights 20 and connected 20 by links 21 with a collar 22 adapted to slide on the hollow shaft 14. This collar is connected by a pin 23 through a slot 24 with an inner shaft or spindle 25, and the end of this spindle is connected with an arm 26 25 which is rigidly attached by an adjustable set screw 27 to the rock shaft 11. Any suitable connection may be made between the inner spindle 25 and the arm 26. I have illustrated this connection as consisting simply of a reduced neck 28 formed on the spindle, which is straddled by a rounded yoke 29. Evidently, when the speed of rotation of the hollow shaft 14 is high, the weights 20 will fly out and tend to pull the collar 22 toward the rock shaft 11. This exerts a thrust and movement in the inner shaft or spindle 25 which moves the arm 26 toward the right, and this will swing the semaphore up toward dotted line position 10°. 30 For operation in daylight the semaphore is sufficient, but when the signal is to be used at night I prefer to provide in conjunction with the signal, a lamp such as the lamp 30, and the semaphore is hung directly in 40 front of this lamp. Furthermore the semaphore preferably is provided with three lenses 31, 32 and 33, the centers of which are arranged in an arc with the axis of the rock shaft 11 as its center. The lens 31 45 is preferably mounted on the central axis of the semaphore arm, but the lenses 32 and 33 are most conveniently mounted in an arc shaped quadrant 34 forming an extension from the semaphore arm. The lenses 31, 50 32 and 33 are of different colors to correspond with any desired conventional signal code, and evidently the signal or message which will be transmitted will depend upon which one of the lenses is disposed before the 55 lamp. The lamp 30 illustrated is supposed to be an ordinary lamp burning kerosene or coal oil.

Vehicles, when not standing still, usually proceed at some predetermined speed, such

as full speed, for instance, quarter speed or 65 half speed. I prefer to arrange the centrifugal device in such a way that when the vehicle is proceeding at half speed the lens 32 will be held before the lamp, and when the vehicle is at full speed the lens 33 will 70 be held before the lamp. The position of the signal illustrated in Fig. 4 corresponds to the danger sign or message. When the lens 32 is before the lamp the signal will indicate "caution," from which it is understood that the vehicle is not proceeding at full speed. The lenses may have any conventional colors, such as red for the lens 31, yellow for the lens 32 and green for the lens 33, or they may correspond to any other 80 signal code desired.

When the signal is applied to the rear end of a vehicle, such as a car 35, the flexible shaft 15 may be driven in any suitable manner, for example by means of a small 85 wheel 36 running on the face of one of the wheels 37 of the rear truck of the car. The wheel 36 may be carried upon a small arm 38, to which is attached a spring 39 which holds the face of the wheel 36 on the 90 wheel 37.

The signal case 13 may be held in place on the rear bolster of the car frame in any suitable manner.

A single signal, such as that described, 95 may be applied to the rear of an automobile, in which case, however, it may not be necessary to indicate an intermediate speed, and it may be merely necessary to indicate the position of the semaphore. Hence in 100 applying the signal to an automobile I prefer to construct the semaphore as indicated in Fig. 3, wherein 40 indicates the semaphore arm having a colored area 41 near its tip and provided with a colored lens 42, 105 behind which a suitable electric light 43 is attached to the semaphore, connection to the light being made through a suitable flexible electric light cord 44. This cable or cord of course permits the necessary 110 movements of the semaphore.

As automobiles are so easily controlled it is not necessary that this signal should indicate a signal to a person at a great distance in the rear, and hence the simple 115 change of position of the light is sufficient to apprise the person driving the following vehicle of the condition of the car carrying the signal.

Where it is desired to have the signal indicate also the direction in which an automobile or car is about to make a turn the semaphores are preferably duplicated. This is most conveniently done by providing a 120 complete signal 45, such as already described, on each side of the car. The construction of the centrifugal devices of these 125 signal devices may be substantially the same.

as that illustrated in Figs. 4 and 5. The flexible shafts 46 may be driven in any suitable manner through the medium of pinions 47 meshing with large gears 48 on the hubs 49 of the wheels 49 and 50. The signal device 45 may be attached to the rear of the automobile body 51. The automobile is supposed to have any common differential drive for the rear axle which may be carried in a 10 suitable differential gear case 52. With such a drive it is well known the wheels 49 and 50 may travel at different speeds. Supposing that the automobile illustrated is turning to the right, then the wheel 49 will 15 be turning very slowly so that its semaphore arm 40 will occupy a nearly horizontal position. The wheel 50, however, will be in more rapid motion and will operate through the centrifugal mechanism of the left-hand 20 signal to cause its semaphore to be raised higher than the other semaphore and occupy some such position as that indicated in the dotted outline 40^a. This double signal is particularly useful at night, as the relative 25 height of the lights will indicate which direction the automobile is turning.

If desired the flexible shafts 46 may be crossed so that the signal which becomes active will lie on the side toward which the 30 vehicle will turn.

The semaphore preferably should not be raised to a vertical position, but only approximately so, and hence even in its uppermost possible position which should be not 35 over about 60 degrees from the horizontal line, it always tends to move down to the horizontal or danger position. Therefore in the present instance I have shown an arrangement which insures that the semaphore 40 arm will not be raised to a true vertical position no matter how high the running speed of the vehicle may be. Referring particularly to Fig. 5 of the drawings it will be seen that case 13 is provided with a short narrow 45 approximately oblong extension or housing 13^a within the parallel side walls of which the rock-shaft 11 is journaled. The end wall 13^b of this extension constitutes a stop to limit the outward movement of the spindle 25, the neck end of such spindle contacting with the bottom of the depression 13^c in the outward movement of the spindle before the semaphore arm can assume a true 50 vertical position. Thus in addition to forming a bearing and housing for the rock-shaft 11, this extension of the casing acts as a stop to limit the vertical travel of the 55 semaphore arm. With this arrangement I avoid the necessity to use any springs, and furthermore I attain a practical advantage 60 in this, that if any part of the signal device becomes broken the signal will come automatically to its danger position. It is also evident that if the vehicle stops from any

cause whatever, as in the case of breaking 65 the running gear of the vehicle, the danger signal will be given automatically. Furthermore, if the machine is out of plumb as it would be when running along a transversely inclined roadway such as a roadway on the 70 side of a hill, the arm will always tend to return from any position, even its highest possible position.

It is understood that the embodiment of 75 the invention set forth herein is only one 80 of the many embodiments or forms the invention may take, and I do not wish to be limited in the practice of my invention nor in my claims to the particular embodiment 85 set forth.

What I claim is:

1. In a rear signal device for vehicles the combination with a casing having a housing extending from one wall thereof, of a rock-shaft journaled in opposite walls of the 90 housing, a signal arm connected with one end of the rock-shaft outside the housing, a rotatable shaft adapted to be driven from a rotating part of the vehicle, centrifugal weights, arms carrying said weights and 95 pivotally connected with said shaft, a spindle connected with said arms and adapted to be moved longitudinally of said shaft, and a loose connection between said spindle and the rock shaft, the outward movement 100 of said spindle under the centrifugal action of the weights raising the signal arm toward a vertical position, the outward movement of the spindle being limited by a part of the housing to prevent said signal arm 105 reaching a true vertical position.

2. In a rear signal device for vehicles a casing having a housing extending laterally and exteriorly from one wall thereof, a rock shaft journaled in opposite walls of the 110 housing, a signal arm connected with the rock shaft, and means for moving said arm toward the vertical when the vehicle is in motion, a part of said housing constituting 115 a stop for limiting the movement of the arm moving means in one direction, and thereby preventing said signal arm reaching a true vertical position.

3. A signal for vehicles comprising a portable casing adapted to be attached to the rear end of the vehicle, a rock shaft, a semaphore arm connected with said rock shaft and adapted under the influence of gravity to normally occupy a horizontal position, a spindle extending at right angles to the rock shaft, a loose connection between the spindle and the rock shaft, a sleeve shaft through which the spindle passes, a collar sliding on the sleeve shaft and connected with the spindle, a second collar fast with the sleeve shaft, centrifugal weights linked to the collars and adapted when the vehicle is in motion to move outward under centrifugal 120 125

force and to shift the spindle in the direction of the rock shaft and move the arm in a vertical direction, and a stop for limiting the movement of the spindle in the direction 5 of the rock shaft and thereby limiting the vertical movement of the arm and preventing the arm assuming a true vertical position.

In testimony whereof I have hereunto set my hand in presence of two subscribing wit- 10 nesses.

HENRY CSANYI.
